(57) **CLAIM**

The ornamental design for a wallet fastener, as shown and described.

DESCRIPTION

FIG. 1 is a top, right, front perspective view of a wallet fastener showing our new design;

FIG. 2 is a top, right, rear perspective view thereof;

FIG. 3 is a front elevational view thereof;

FIG. 4 is a right side view thereof, the left side view being a mirror image thereof;

FIG. 5 is a rear elevational view thereof; and,

FIG. 6 is a bottom plan view thereof, the top plan view being a mirror image thereof.

The broken lines showing a wallet affixed to the wallet fastener of FIG. 1 are for purposes of showing environmental structure only and form no part of the claimed design.
